UNITED STATES PATENT OFFICE.

WILLIAM BENTON CUPPETT, OF PORTSMOUTH, OHIO.

VENEERED AND REINFORCED WOODWORK.

1,133,106.

Specification of Letters Patent. Patented Mar. 23, 1915.

Application filed December 20, 1913. Serial No. 807,922.

To all whom it may concern:

Be it known that I, WILLIAM BENTON CUPPETT, a citizen of the United States, residing at 1407 Ninth street, Portsmouth, 5 in the county of Scioto and State of Ohio, have invented certain new and useful Improvements in Veneered and Reinforced Woodwork; and I do hereby declare the following to be a full, clear, and exact description of the invention, such as will enable others skilled in the art to which it 10 appertains to make and use the same.

The object of the invention is to provide an improved construction of reinforced veneer woodwork for furniture and the like.

A further object is to provide a veneer for furniture in which the top and edge surfaces shall be perfectly matched in grain, so as to closely resemble a solid piece of 20 thick material.

A further object is to generally improve the construction and appearance of veneered work and materially cheapen the cost of manufacture thereof.

25 In the accompanying drawing wherein is shown an approved embodiment of the invention, Figure 1, represents a fragmentary perspective view of a corner of a bookcase cover or the like, constructed in accordance 30 with my invention. Fig. 2, represents a sectional view therethrough. Fig. 3, represents a similar view of a modified form of the invention. Figs. 4 and 5, represent fragmentary sectional views of the form of 35 veneer employed in the construction of work shown in Fig. 3. Fig. 6 represents a fragmentary perspective view of the blank showing the manner in which the same is cut.

Referring to the drawing in detail, 1 indicates the core of the material preferably 40 formed of defective rotary cut stock. 2 indicates any desired number of face auxiliary layers of wood and 3 indicates the similar back. The core 1 and crossings 2 and 3 are 45 suitably glued or otherwise fastened together with their grains crossing at right-angles successively and thereafter the veneer 4, which may be of any grade or kind of wood desired, is suitably secured over the 50 face layers and the back 5 secured to the inner face.

In constructing furniture covers, table tops and the like, in accordance with my invention, I join the core, layers, back and veneer in the manner above described after 55 they have been cut to a measurement including the length and width of the top and the width of the turned edges 6 representing the thickness of the material in the finished article. As shown in Fig. 6, I cut 60 V-shaped grooves 7 in the back of the blank on lines spaced from the sides and edges of the latter representing the desired thickness of the finished article. The grooves 7, as will be understood, may be machined and 65 are formed so that the parts when joined together will fit perfectly. The cuts or grooves 7 are also formed of sufficient depth so as to just penetrate the surface of the veneer 4, as clearly shown in Fig. 2. 70

To fit the blank together after the same has been cut or grooved, the corners 8 are removed and the edges 9 are turned down and the beveled faces formed by the grooves 7, fitted and glued together so as to provide 75 a finished article, as shown in Fig. 1, wherein the grain of the top and edge surfaces match and appear as a solid piece of material cut in any desired rectangular form.

In the modification of my invention as 80 shown in Figs. 3, 4, and 5 the grooves 7, terminate a distance short of the outer surface of the veneer 4, and folding the blank to provide the finished article partially rounds the corners of the veneer and 85 presents an exceptionally neat and desirable appearance.

Having thus fully described my invention what I claim as new and desire to secure by Letters-Patent is:

As an improved article of manufacture, veneered woodwork having the top and edge surfaces so matched as to simulate a solid piece of the costly material forming the veneer, the said improved construction including a costly veneer, a cheap core and backing secured thereto, a pair of V-shaped notches being cut from said backing upward to just penetrate the inner surface of the veneer at each point, the said notches being 100 at right angles to each other and intersecting to allow for the entire removal of the

piece embraced between the notches of each pair to enable the bending of the sides of the pieces of wood work to bring opposite faces of each pair of notches into conjunction thus presenting edge surfaces for a piece of veneered wood work exactly matching the top thereof in simulation of a solid piece of material forming the veneer.

In testimony whereof I have signed my name to this specification in the presence of 10 two subscribing witnesses.

WILLIAM BENTON CUPPETT.
